Inventor,

Ralph Brownson

by A. S. Johnson
his Attorney.

UNITED STATES PATENT OFFICE.

RALPH BROWNSON, OF HASTINGS, MINNESOTA.

MOP WRINGER.

1,426,456.

Specification of Letters Patent. Patented Aug. 22, 1922.

Application filed March 29, 1919. Serial No. 286,107.

To all whom it may concern:

Be it known that I, RALPH BROWNSON, a citizen of the United States, residing at Hastings, in the county of Dakota and State 5 of Minnesota, have invented certain new and useful Improvements in Mop Wringers, of which the following is a specification.

This invention relates to improvements in mop wringers and the like, and more particularly to that portable type of wringer, 10 wherein the wringing devices are secured to a pail or other water holding receptacle.

An object of the invention is to provide a device of the class described, which will 15 have a relatively large unobstructed open top, presenting a comparatively large water surface, to afford ample room for thoroughly rinsing the mop, before subjecting it to the wringing process. Another object of the 20 invention is to provide, in a device of the class described, certain novel structural features whereby a strong upper edge is secured, though the body of the receptacle be made of comparatively thin sheet metal.

25 A further object of the invention is to provide a device of the class described, which may be easily operated as by the use of the foot for applying pressure directly to the mop, the receptacle designed with a capacity 30 of an ordinary pail, but of lesser height than the latter.

To this end, the invention consists in the features of construction, combination and arrangement of parts, hereinafter described 35 and claimed.

Fig. 1 is a perspective view of a mop wringer embodying the invention.

Fig. 2 is aside elevation of same, the near side removed to show the normal position of 40 the parts.

Fig. 3 is a perspective view of the movable wringer roll support, and

Fig. 4, is a fragmentary vertical sectional view through the upper edge of the receptacle, through the bearing of the stationary wringer roll.

50 Referring to Fig. 1, A represents a tank or receptacle having a beaded upper edge 1, formed by rolling the metal of the side walls over the re-enforcing wire 2, the metal of the side walls, extending downwardly beyond the wire and lying flat against the side walls, so as to form a comparatively wide auxiliary web 3, throughout the length 55 of the tank A.

The tank as shown is rectangular in shape

and comparatively long and shallow. Adjacent one end of the tank and journaled in the side walls is the stationary wringer roll 4. The roll 4 has longitudinally thereon a central spindle 5, which latter loosely pierces with its respective ends the respective side walls and their respective webs 3. The spindle is formed at each end with a head 6, whereby the webs 3, at both sides of the tank are held against buckling outwardly. At the opposite end of the tank is pivotally mounted by means of the pivot pin 7, the movable wringing element B, comprising a rectangular frame having bent 70 side members 8 joined together at one end by the cross member 9. The outer ends of the side members support rotatably by means of the pin 10 the wringer roll 11, which latter, when swung about the pivot 7 75 is adapted to roll with its circumferential surface on that of the roll 4. The frame of element B is of a length to bring the axis of the pin 10 and the spindle 5, longitudinally in a plane (indicated by dotted lines in Fig. 80 2) disposed at an inwardly and upwardly extending angle to the end wall of the tank. Thus a downward pressure brought to bear on the element B, effects a leverage and places the members 8 in compression and 85 the pivot pins 7 and pin 5 in shear in the side walls of the tank. The re-enforcing web 3, however affords sufficient and additional bearing surface for said pins thereby preventing swaging and bending at the 90 bearings of the light sheet metal of which the side walls are made. A foot block 12, having shoulders 13 in its upper face, connects the members 8 rigidly together near their outer ends.

95 As indicated in dotted lines in Fig. 2, the shoulder 12 is adapted to engage the heel of the shoe, to enable the operator to obtain a firm foot hold, to press the element B firmly downward against the mop, while the latter is pulled upwardly away from the rolls. The element B may then be swung about the pivot 7 to assume the position shown in Fig. 2. It will be noted, that the 100 roll 4 and pivot pin 7 alone obstruct the tank opening, leaving a comparatively large water surface easy of access. As shown, the entire wringing mechanism lies normally, wholly within the tank opening, leaving no 105 obstructing projections above the tank line. This is important, as the tanks may be readily stacked one upon another for shipping.

A bail 14, having hooks 15 adapted to receive the bead 1 in the end walls of tank, is formed to conform to the rim contour of the tank when lying on its side. A comparatively small filler roll 16 serves to cover pivot rod 7 to guard against accidental bending of the latter.

I claim:—

A mop wringer comprising a tank open 10 at its top and having web-extensions along the upper side edges, a reinforcing wire secured along the upper edges by bending said web-extensions downwardly thereover, spindles extending transversely across the

tank and having their opposite ends extending through the opposite sides of the tank and the overlying web-extensions the outer ends of said spindles being headed to secure the spindles and web-extensions in place, a wringer roll supported on one spindle, and a wringer-roll-supporting frame journaled on the other spindle. 15 20

In testimony whereof I affix my signature in presence of a witness.

RALPH BROWNSON.

Witness:

GEORGE VOELKER.
